(57) **CLAIM**

The ornamental design for a stool, as shown and described.

DESCRIPTION

FIG. 1 is a right side elevation view of a stool showing my new design, the left side being the mirror image thereof; FIG. 2 is a front elevation view thereof, the rear elevation view being the mirror image thereof; FIG. 3 is a top plan view thereof; FIG. 4 is a bottom plan view thereof; FIG. 5 is a front side perspective view thereof; FIG. 6 is a view similar to FIG. 5 but showing how two stools can nest with each other; FIG. 7 is a front and side perspective view of an inverted stool, and, FIG. 8 is a front and side perspective view of a stool of the invention, resting on its back. The broken lines in FIG. 6 depict environmental subject matter and forms no part of the claimed design.
